UNITED STATES PATENT OFFICE

JOHN RUSSELL EMMERT, OF CHICAGO, ILLINOIS, ASSIGNOR TO EMIL J. PAIDAR COMPANY, OF CHICAGO, ILLINOIS, A CORPORATION OF ILLINOIS

DESIGN FOR A MORGUE TABLE OR SIMILAR ARTICLE

Application filed January 16, 1929. Serial No. 29,635. Term of patent 14 years.

To all whom it may concern:

Be it known that I, JOHN RUSSELL EMMERT, a citizen of the United States, and a resident of the city of Chicago, in the county of Cook and State of Illinois, have invented a new, original, and ornamental Design for a Morgue Table or Similar Article, of which the following is the specification, reference being had to the accompanying drawing, forming a part hereof.

In the drawing:

The figure illustrates a perspective view of the morgue table showing my new design.

I claim:

The ornamental design for a morgue table or similar article, as shown.

JOHN RUSSELL EMMERT.
